FREEMAN R. WILLSON, JR., OF WORTHINGTON, OHIO, ASSIGNOR, BY MESNE ASSIGNMENTS, TO THE JEFFREY MANUFACTURING COMPANY, A CORPORATION OF OHIO.

PULVERIZING-MACHINE.

1,084,516.

Specification of Letters Patent.

Patented Jan. 13, 1914.

Application filed July 15, 1905. Serial No. 269,862.

To all whom it may concern:

Be it known that I, FREEMAN R. WILLSON, Jr., a citizen of the United States, residing at Worthington, in the county of Franklin 5 and State of Ohio, have invented certain new and useful Improvements in Pulverizing-Machines, of which the following is a specification, reference being had therein to the accompanying drawing.

10 This invention relates to machines for pulverizing or finely subdividing material, in which are employed a series of rotating beaters or hammers mounted upon a horizontal shaft. The material after being finely subdivided or pulverized, is carried out of the machine by means of air currents.

In the drawings, Figure 1 is a rear elevation of a machine embodying my invention; Fig. 2 is a central vertical section; Fig. 3 is a bottom plan view of the breaking nose; Fig. 4 is a plan view of one of the plates that form the grinding or pulverizing surface; Fig. 5 is a cross sectional view of the plate shown in Fig. 4. Fig. 6 is an end view 25 partly in section of a portion of the apparatus serving to show the means for adjusting the bearings of the beater shaft.

In the drawings, A represents a horizontal shaft upon which are mounted a series of spiders or arms B, to which are pivotally connected the hammers or beaters C. These parts, which may be of any usual or preferred construction, are mounted within a casing D, and are driven at a high speed by power from a suitable motor, which may be applied through the pulley E on the outer end of the shaft.

The chamber within the casing, wherein the grinding and pulverizing action takes place, is approximately cylindrical in shape. At one side the casing is provided with an enlargement or extension in the form of an inclined duct F.

G represents a hopper for containing the material that is to be fed to the beaters. It delivers to a feed-board H, and this in turn, passes the material into one side of the duct F that leads to the pulverizing chamber of the machine. It will be observed that the feed-plate H is so located that the material falls therefrom upon the down-moving hammers, in other words, the material is fed to the machine in the direction, or substantially the direction, of movement of these hammers or beaters with which it first comes into

engagement. Arranged on the side of the duct F, opposite to the feed-plate H, is the breaker plate I which is formed of a relatively heavy and rigid piece or pieces of metal. The grinding or pulverizing surface 60 is formed of a series of segmental ribbed plates K, one of which is illustrated in Fig. 4, arranged quite close to the outer ends of the hammers or beaters C. In order to increase the disintegrating and pulverizing 65 efficiency of the grinding surface, the plates K are constructed to have a series of ribs k, produced by forming channels or grooves in the plates. These ribs tend to retard the forward movement of the material, and thus 70 subject it to the action of the hammers, largely increasing the efficiency of the machine, as compared with one in which the grinding surface is formed of plates having smooth surfaces. It will be seen by reference to Fig. 4, that the ribs are inclined toward the center of the plate. This tends to force the material toward the center of the machine, and prevents the accumulation 75 thereof at the ends of the casing. The grinding 80 surface in the upper segment of the machine is so disposed that it gradually recedes from the path of the outer ends of the hammers, leaving a free space between the hammers and such surface.

L represents the breaking nose, an abutment or stop situated at the end of the grinding surface, and having a substantially vertical wall or face l. The material that has been carried around the grinding or 85 pulverizing surface by the action of the hammers or breaking bars is arrested by this wall of the breaking nose, whether such material be finely pulverized or still un-reduced, and is thereby forced toward the 90 hammers to be again caught by them and further acted upon. It has heretofore been customary to arrange the vertical face of the breaking nose in a plane extending 95 straight across the machine transversely. I have found that better results are obtained if this face is somewhat dished, as represented in Fig. 3, as the inclined portions l' of the wall tend to force the material caught thereby toward the center of the machine.

100 M represents an air trunk to which is connected any suitable apparatus for causing a current of air to pass through the same. The trunk M is connected at its lower or inlet end with one side of the duct F lead-

ing into the pulverizing chamber of the machine. I prefer that the opening *m* into the trunk should be adjacent to, and just in advance of, the lower or delivery edge of the 5 feed plate *H*, so that the material delivered into the machine is immediately subjected to the air currents passing from the inlets *a* to the outlet *m*, and light material that may be carried thereby is at once carried off without 10 being subjected to the action of the beaters. It will be observed that there are two openings into the casing at the outer end of the duct *F*, one of these openings being that at *m*, and the other being on the opposite side 15 of the wall of the duct *m* and being adapted for the admission of material discharged from the plate *H*. The material to be pulverized is delivered from the plate *H* in a broad stream moving along a path the width 20 of which is substantially the width of the pulverizer casing. The proximity of the impact nose or stop *L* to the opening *F* results in the material falling from said stop also being subjected to the direct action of the air 25 currents. At the same time it will be observed that the pulverized material is taken up by the air draft at a point remote from the region in which the grinding action of the hammers takes place.

30 At *N*, is arranged a series of baffle plates which operate to regulate the force of the air currents through the trunk *M* accordingly as they are adjusted.

The feed-plate is suitably connected with 35 bell-crank levers *P* that are vibrated by means of rods *Q* that receive their motion from eccentrics *R* on shaft *S*. The shaft *S* is belted to a pulley *s* on the shaft *A*, receiving therefrom a relatively slow motion. 40 In order to regulate the feed, I support the rear end of the feed-board on a roller *T*, the shaft of which is supported in slots *t* so as to be adjustable. By raising or lowering the roller *T*, the inclination of the feed-plate may be varied, and the feed accordingly accelerated or retarded.

O represents a slide-valve mounted in the hopper *G* above the feed-plate. The upper segment of the grinding surface is covered by a plate *U* curved to fit the outer surface of the grinding plates. In order to permit the adjustment of the beaters or hammers relative to the grinding or pulverizing surface at the bottom of the machine, I preferably mount the bearings for the horizontal shaft *A* so that they are capable of bodily adjustment toward the said grinding surface. This may be done in any suitable way, for instance, as is clearly shown in Fig. 6 45 by making the bearing wedge-shaped and seating it in a correspondingly shaped seat in the frame. Shims *u* and *v* are placed upon each side of the bearing so that by removing shims from one side or the other only the bearing may be shifted horizontally

and by removing equal thicknesses of shims from both sides the bearing may be adjusted vertically.

I have in Fig. 2 indicated in dotted lines at *a* an elongated aperture through the side wall of the machine. Another such aperture is provided on the opposite side of the machine and through these the shaft *A* extends. It will be seen that the shaft can be adjusted up and down within these apertures so as to bring the lower edges of the hammers or beaters *C* into different positions relative to the grinding surface. These elongated apertures *a* also serve as openings through which air may enter the interior of the casing or framework adjacent to the pulverizing or grinding surface.

The machine may be utilized for grinding and pulverizing various materials in which the finely reduced particles may be drawn off or separated from the heavier materials by air currents, such as lime, limestone, coal, minerals and the like.

What I claim is:

1. In a pulverizing machine, the combination of a casing having an interior grinding or pulverizing surface, a set of rotating beaters or hammers mounted in said casing to coöperate with said grinding surface, and an inward projecting impact nose or stop 90 for the material arranged substantially parallel to the axis of rotation in planes beyond the end of the pulverizing surface and having the ends of its impact surface dished or inclined toward the central planes of action of the hammers, substantially as set forth.

2. In a pulverizing machine the combination of a casing provided with an interior grinding or pulverizing surface, a set of rotating beaters or hammers, within said casing, to coöperate with the said grinding surface, and an impact nose or stop so located that material will be driven against it by the action of the hammers, the said casing having an air inlet opening, an air outlet opening through which pulverized material may be drawn by air currents and a feed opening 105 separate from the air inlet opening for supplying material to the casing, the said impact nose and the said feed opening being in planes intermediate the air inlet opening and the air outlet opening whereby material falling from the said nose and from the said feed opening is subjected to the direct action of the air current passing from the inlet opening to the outlet opening, substantially 110 as set forth.

3. In a pulverizing machine, the combination of a rotary hammer mechanism and a casing inclosing said hammer mechanism and having a grinding surface and a breaking plate adjacent the grinding surface and at a distance from the outer swing of the hammer mechanism, said casing having a 125 130

feed opening above the hammers and above the breaking plate whereby material falling from the feed opening will be driven by the hammers against the breaking plate, the 5 said casing also having air inlet and air outlet openings separate from the feed opening, the air outlet opening being at the side of the path of the material from the feed opening to the breaking plate opposite to the hammer mechanism, and the air inlet opening being at the same side of the path

as the hammer mechanism, whereby fine material falling from the feed opening or formed at the breaking plate is carried outward away from the hammer mechanism, substantially as set forth.

In testimony whereof I affix my signature, in presence of two witnesses.
